Primary Examiner — Lilyana Bekic*Assistant Examiner* — Mary Shannon Malley(74) *Attorney, Agent, or Firm* — Plumsea Law Group, LLC(57) **CLAIM**

The ornamental design for an electronics case, as shown and described.

DESCRIPTION

FIG. 1 is a perspective view of an electronics case showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof;

FIG. 7 is a bottom view thereof; and,

FIG. 8 is a perspective view thereof, shown in an open configuration.

The broken lines depict portions of the electronics case that form no part of the claimed design.

1 Claim, 8 Drawing Sheets(56)
